EX

OR D 12,379

No. 12,379

Aug. 2, 1881

UNITED STATES PATENT OFFICE.

RODOLPHE CHRISTESEN, OF NEW BRITAIN, CONNECTICUT, ASSIGNOR TO
THE RUSSELL & ERWIN MANUFACTURING COMPANY, OF SAME PLACE.

DESIGN FOR A DROP-LETTER PLATE.

SPECIFICATION forming part of Design No. 12,379, dated August 2, 1881.

Application filed May 25, 1881. Term of patent 7 years.

To all whom it may concern:

Be it known that I, RODOLPHE CHRISTESEN, a citizen of the United States, residing at New Britain, in the county of Hartford and State of Connecticut, have invented and produced a new and original Design for a Drop-Letter Plate, of which the following is a specification, reference being had to the accompanying engraving, forming part thereof, which represents the same in perspective.

The contour of the plate forms a rectangular figure with slightly-rounded corners. It is bordered by a raised ledge, the same being double for the greater portion of the vertical sides, and connected with double cross-bars *a*, short and single transverse bars *b*, and vertical bars *c*, which divide the face of the plate into eight small panels, four on each of the longest sides, and three middle panels, as shown. The eight smaller panels are ornamented by raised figures consisting of small squares in groups of five. The upper middle panel is ornamented by a rosette and two leaflets on a vertical stem, the lower middle panel by a rosette and leaflets joined to a stem upon each side of the rosette. The central panel or letter-mortise has curved brackets at its four corners, the word "letters" arranged vertically on its face, and the two side wings are ornamented by a rosette, all as shown.

I claim—

1. The design for a drop-letter plate herein shown and described, the same consisting of the several raised ledges connected together and forming the eight small panels along the two vertical sides, and between them the three middle panels. 35

2. The design for a drop-letter plate herein shown and described, the same consisting of the central panel having side wings ornamented by rosettes, and the smaller panels by the side of the central panel, arranged above and below the side wings, and ornamental work in relief inclosed within said smaller panels. 40

3. The design for the drop-letter plate herein shown and described, the same consisting of the several raised ledges connected together and forming the eight smaller panels along the two vertical sides, and between them the three middle panels, the former being ornamented by the groups of squares and the latter by the rosettes, leaflets, and letters. 45 50

RODOLPHE CHRISTESEN.
